UNITED STATES PATENT OFFICE.

GEORGE WASHINGTON, OF NEW BRIGHTON, NEW YORK, ASSIGNOR, BY MESNE ASSIGNMENTS, TO JOSEPH N. PATTERSON, OF DEVON, PENNSYLVANIA.

LAMP.

SPECIFICATION forming part of Letters Patent No. 770,836, dated September 27, 1904.

Application filed August 15, 1901. Serial No. 72,198. (No model.)

To all whom it may concern:

Be it known that I, GEORGE WASHINGTON, of New Brighton, in the county of Richmond and State of New York, have invented certain new and useful Improvements in Lamps; and I do hereby declare the following to be a full, clear, and exact description of the invention, such as will enable others skilled in the art to which it appertains to make and use the same.

10 My invention relates to an improvement in lamps, and more particularly to a frame for incandescent lamps, an object of the invention being to provide improved means for removably securing the vaporizing-tube in place 15 and permitting its removal without disturbing the other parts of the lamp.

A further object is to provide an improved frame to independently and removably support the burner and vaporizer.

20 A further object is to provide improved air-inlet tubes which will take the air from outside the lamp and below the point of burning to insure the supplying of pure oxygen to the burner.

25 A further object is to provide an improved lamp whose component parts can be readily and quickly assembled and any part thereof which may become broken or injured easily replaced by any one of average intelligence.

30 With these objects in view the invention consists in certain novel features of construction and combinations and arrangements of parts, as will be more fully hereinafter described, and pointed out in the claims.

35 In the accompanying drawings, Figure 1 is a view in elevation illustrating my improvement. Figs. 2 and 2^a are views of the main portion of the lamp-frame. Fig. 3 is a view in vertical section with parts removed. Fig. 4 is an enlarged detail view in section of the vaporizing-tube and oil-supply connection. Fig. 5 is a plan view of top of main frame. Figs. 6, 7, and 8 are views of modified forms of my invention.

40 1 represents a pipe provided at its upper end with a coupling 2 for its attachment to the gas-pipe or other support. The lower end of the pipe 1 is screwed into a casting 4, provided with ducts 5 for the reception of the 45 ends of a circular pipe 5^a around the vapor-

izing-tube and perforated on its inner side for burning the gas to start preliminary vaporization. The casting 4 is provided on opposite sides with notched ears 6 for the reception of the upper ends of long screws 7, having nuts 55 screwed thereon to secure a horizontally-disposed ring 8, which, with the parts carried thereby, constitutes the main portion of the frame, said screws 7 also passing through lugs 9, projecting outward from a tubular extension 10 on a sleeve 11, and spacing-sleeves 12 are provided on the screws 7 between the lugs 9 and ring 8. The flanged upper edges 14 of semiconical shields 13 are perforated to receive the screws 7 to hinge the shields and 60 hold their flanged upper ends 14 against the bottom of ring 8 by means of the spacing-sleeves 12, the hinged ends of said flanges 14 being cut away to permit them to swing, the free ends of the shields being brought together to entirely close the space between the ring 8 and sleeve 11 and prevent drafts up 65 through the lamp.

The tubular extension 10 is internally threaded for the reception of an externally-threaded 70 sleeve 15, having an angular head 16 at its outer end to receive a wrench for turning it, and the head 16 is internally beveled to countersink the head of a screw 17, which latter projects through the sleeve 15 and is screwed 75 into a sliding plug 18, provided on its upper face with a lug 19 to move in a slot in the extension 10 and prevent rotary movement of the plug. The plug 18 is provided in its outer end with a horizontal oil-duct 19^a, having a 80 short connecting-duct 20 projecting up therefrom and with which the oil-pipe 21 communicates. The oil-pipe 21 is flexible and secured to the plug 18 in any desired manner and connects the duct 20 therein with a duct 85 22 in the casting 4, with which duct 22 an oil-supply pipe 23, inclosed in a pipe 1, communicates, and said pipe 23 projects up through the coupling 2 and is closed at its upper end and has an opening in its side alining with a 90 threaded hole in the coupling 2 for the attachment of a supply-pipe connecting the same with a suitable oil-tank. However, the oil-supply pipe may be secured to the outside 95 of pipe 1 if desired.

The inner end of plug 18 is beveled or sharpened and is adapted to be forced inward by the sleeve 15 into an opening in the side of an approximately cylindrical block 25 on the 5 lower end of the vaporizing-tube 26, with which opening the vaporizing-chamber communicates. The plug 18 when forced into the opening in the block 25 not only serves to connect the oil-supply with the vaporizing- 10 tube, but also serves to hold the tube in the sleeve 11 and permit its ready removal by simply loosening the sleeve 15 to draw the plug 18 out of the opening in the block, when the vaporizing-tube will drop down through the 15 sleeve 11 without disturbing any part of the lamp. The block 25 also contains the means for operating the ordinary needle-valve in the vaporizing-tube, and said operating means is provided with a shaft projecting through the 20 side of the block and having a cylindrical enlargement 26^a on its outer end, which is made with a peripheral groove to receive a screw 27, screwed through a ring 28, disposed on the enlargement, and said screw is provided 25 on its free end with a knob or button 29 to facilitate turning it and secure it to the enlargement 26^a. It will be seen that by providing this improved device the screw can be set at any angle, according to the position of 30 the lamp, to most conveniently operate the needle.

The ring 8 is provided on its inner face, equidistant apart, with a series of pockets 27, into which the lower ends of the air-inlet 35 tubes 29 are removably supported, and said pipes are cut away at their lower ends at an angle to expose the interior thereof to the atmospheric air supplied through holes 28 in the sides of the ring 8 or in the bottom thereof, as preferred, and as this ring is located 40 below the point of combustion the air taken in by the tubes 29 is free from the burnt gases. This commingling-chamber and burner-tube 30 are of the ordinary construction and have 45 provided on their lower ends the auxiliary burner 31, which may be made integral with either the burner-tube or the vaporizing-tube or may be made separate and removably secured in place.

50 A removable sleeve 32 is supported between the tubes 29 to direct the flame for preliminary heating against the vaporizing-tube when a wick saturated with alcohol is used; but when gas is employed for preliminary 55 heating there is no necessity for this sleeve 32, and it can be dispensed with.

An incandescent mantle of ordinary construction is supported on the main burner-tube, and a small gas-jet 32^a projects from 60 pipe 1 to light the same. A chimney 33 is secured above the mantle, and to the tube 1, by means of a clamp 34, on one side of said chimney, is provided at its upper end with a deflector 35 and at its lower end with a small 65 reflector 36. The tube 1 is bent to centrally

dispose the chimney 33 and is provided near its upper end with an adjustable collar 37, on which a large chimney 38, having hoods 39 at its top, is supported, and a large reflector 40 is secured to the lower end of the chimney 38 to throw the light down onto the ground when the lamp is hung high; but when the lamp is low this reflector 40 can be dispensed with.

A globe 41, inclosing the burner, is held 75 against the chimney 38 and is supported on a flanged ring 42, which latter is provided with internal lugs 43 to support the ring 42 and globe in place, as will now be explained. The ring 8 is provided beside each air-inlet opening with a vertical groove 44, communicating with said opening by a short groove 45, and the lugs 43 are pushed up in the vertical grooves 44 and the ring 42 turned to move the lugs 43 through the grooves 45 into the air-inlet 85 openings in which they rest and are supported, and when it is desired to remove the globe it is simply necessary to lift the ring 42 and turn it slightly until the lugs 43 move into the vertical grooves 44, when the ring 90 and globe can be slipped down and off. The ring 42 is made with holes to align with the holes in the ring 8, so as not to interfere with the supply of air to the burner.

Instead of providing the construction of 95 oil-pipe and vaporizer connection above described I might employ a joint connection, as shown in Fig. 6. In this form of my invention a tubular screw 46 is screwed through sleeve 11 and carries the end of oil-pipe 47, to 100 which is secured at its extreme end a conical jam 48, which is adapted to be forced into the opening in the vaporizer or removed therefrom to make or break oil connection therewith.

Instead of constructing the main frame as 105 above described I might construct the same as shown in Fig. 7, wherein I provide a depending arm 49 on one side of ring 8 and mount in its lower end the oil-pipe coupling 50, which is adapted to be secured into and support the vaporizer, hence dispensing with the sleeve 11 and all connecting parts between the same and ring 8. This arm may be made 110 separate or cast with ring 8. This frame may, if desired, be used on a bracket-lamp by connecting the same at one side to the bracket by any well-known means.

I make no claim in this application to the shade or globe support herein shown and described, but reserve the right to claim same in a separate and subsequent application.

Various slight changes might be resorted to in the general form and arrangement of the several parts described without departing 125 from the spirit and scope of my invention, and hence I would have it understood that I do not wish to limit myself to the precise details set forth, but consider myself at liberty to make such slight changes and alterations 130.

as fairly fall within the spirit and scope of my invention.

Having fully described my invention, what I claim as new, and desire to secure by Letters Patent, is—

- 5 1. In a lamp the combination of a frame or bracket having two seats or supports, a burner carried by one seat or support and a vaporizer by the other, the said burner and vaporizer being each independently removable from said seats or supports.
- 10 2. In a lamp, the combination with a frame or bracket having two independent seats, of a burner secured on one of said seats and a removable vaporizer to the other, an oil-supply pipe, and a coupling for connecting the oil-supply pipe to the vaporizer and for locking the latter to its seat whereby when the oil-supply pipe is disconnected the vaporizer is free to be removed from its seat.
- 15 3. A lamp-frame comprising a ring forming a burner-support, a sleeve below the same adapted to receive a vaporizer and connecting devices between the ring and sleeve.
- 20 4. In a lamp the combination with a supporting-frame, and a sleeve secured to said frame, of a tubular extension on said sleeve, a sliding plug mounted in said extension, an oil-supply pipe connected to said plug and supplying oil to a duct therein, a vaporizing-tube having an opening in one side and adapted to be inserted in said sleeve and means for forcing said plug into the opening in the vaporizing-tube to connect the oil-supply therewith and support the tube in operative position.
- 25 5. In a lamp the combination with a sleeve and a tubular internally-screw-threaded extension thereon, of a plug mounted to slide in said tube and having an oil-duct therein and a beveled end, a sleeve screwed into said tubular extension, a screw in said last-mentioned sleeve screwed into the plug, an oil-supply pipe communicating with the duct in said plug, and a vaporizing-tube disposed in said first-mentioned sleeve and having a hole in one side to receive the plug and secure the vaporizing-tube in place and connect it with the oil-supply.
- 30 6. In a lamp, the combination with a supporting-tube to be connected to the gas-supply, the said supporting-tube carrying means for supporting a shade or globe, and independent means for removably supporting the vaporizer in place, of an oil-supply pipe leading to said vaporizer, a burner into which said vaporizer discharges, a gas-burner leading from the supporting-tube to a point adjacent to the vaporizer for imparting initial heat to the latter, and a gas burner or jet leading from said supporting-tube to a point near the vapor-burner for lighting the latter.
- 35 7. In a lamp, the combination with a supporting-tube for connection with a gas-supply, the said tube carrying a seat for a globe

or shade and an independent seat for the attachment of a removable vaporizer, of a vapor-burner into which the vaporizer discharges, an oil-supply pipe located within the supporting-tube and coupled up with the vaporizer a gas-burner tube leading from said supporting-tube and located adjacent to the vaporizer for starting initial vaporization in the latter and a gas-burner adjacent to the vapor-burner for lighting the latter.

75 8. In a lamp, the combination with a ring and a burner supported thereon, of a sleeve below the ring and of smaller diameter, bolts securing said ring and sleeve together, a vaporizing-tube supported in said sleeve and supplying vapor to the burner, semiconical shields closing the space between the sleeve and ring, flanges on the upper ends of said shields having holes therein for the reception of the bolts to hinge the shield and spacing-sleeves on said bolts to hold the flanged upper ends of the shields against the ring.

80 9. The combination with a support or frame having a seat for a vapor-burner and an independent seat for the vaporizer of a sectional shield hinged to said frame and adapted to 90 close the vaporizer.

95 10. The combination with a supporting-frame having a seat for a vapor-burner and an independent seat for the vaporizer, of a sectional shield hinged to said frame and embracing the seat for the vaporizer, substantially as set forth.

100 11. In a lamp, the combination with a vaporizer, and a valve therein, of a shaft for operating said valve, an enlarged free end on said shaft, a ring on said enlarged end, and a long screw screwed through the ring and against the enlarged end of the shaft to form an adjustable lever for turning the shaft.

105 12. In a burner of the type recited, the combination of an outer tubular casing, a mixing-tube concentrically mounted in said casing, downwardly-extending air-intake tubes supporting said casing and mixing-tube and communicating with the latter, said mixing-tube being arranged relative to the casing to provide an annular compartment for oil-gas and air intermediate said casing and mixing-tube, a bracket supporting said air-intake tubes, a vaporizing-tube penetrating the base of said casing and detachably confined centrally of the bracket, a subburner surrounding the discharge end of the vaporizing-tube and communicating with said compartment, and means for concentrating the flames from the subburner upon the discharge end of the vaporizing-tube.

115 13. In a burner of the type recited, the combination of an outer casing, a mixing-tube concentrically mounted in said casing, downwardly-extending air-intake tubes supporting said casing and mixing-tube and communicating with the latter, said mixing-tube being arranged relative to the casing to provide a com-

- partment for oil-gas and air, means for deflecting oil-gas and air into said compartment, a bracket to which said air-intake tubes are detachably connected, a vaporizing-tube penetrating the base of the casing and detachably mounted relatively to the bracket and casing, and a member closing the space between the bottom of the mixing-tube and the casing and perforated to provide a subburner.
14. In a burner of the type recited, the combination of an outer casing, a mixing-tube within said casing, air-intake tubes supporting said casing and mixing-tube and communicating with the latter, said mixing-tube being arranged relative to the casing to provide an annular compartment for oil-gas and air, a circular deflector disposed above the mixing-tube for deflecting portions of the mixture of oil-gas and air into said compartment, a bracket having means for detachably supporting said air-intake tubes, a vaporizing-tube penetrating the base of the casing and detachably mounted relatively to the bracket and casing, and a member closing the space between the bottom of the mixing-tube and the casing and perforated to provide a subburner.
15. In a burner of the type recited, the combination of an outer casing, a mixing-tube within said casing, a burner-head mounted on said casing and having an inner circular deflector, downwardly-extending air-intake tubes supporting said casing and mixing-tube and communicating with the latter, said mixing-tube being arranged relative to the casing to provide a compartment for a portion of the mixture of oil-gas and air, a bracket having means for detachably supporting said air-intake tubes, a vaporizing-tube discharging oil-gas through said mixing-tube against the deflector, and detachably arranged with reference to the bracket and casing, and a member closing the space between the bottom of the mixing-tube and the casing and perforated to provide a subburner.

16. The combination with the burner and mixing-tube, of a vaporizing-tube discharging oil-gas across an air-space into said mixing-tube and provided with an oil-inlet, a bracket having an upper horizontal tubular part, a hollow plug movable in said tubular part toward and away from said inlet and adapted for communication with said vaporizing-tube via the inlet, means for causing said plug to communicate with the vaporizing-tube and to simultaneously clamp said vaporizing-tube in the bracket, and oil-supply connections communicating with said hollow plug.

17. The combination with the burner and mixing-tube, of a vaporizing-tube discharging oil-gas across an air-space into said mixing-tube and having an oil-inlet, a bracket in which said vaporizing-tube is detachably fitted, a hollow plug movable in said bracket toward and away from the inlet of the vaporizing-tube for establishing and disestablishing communication with the latter, means for causing said plug to simultaneously clamp and communicate with the vaporizing-tube, and oil-supply connections communicating with said hollow plug.

18. In a burner of the type recited, the combination of a burner-casing, a mixing-tube therein, air-intake tubes supporting the casing and mixing-tube and communicating with the latter, a vaporizing-tube penetrating the base of the casing, a bracket having a recess to receive the vaporizing-tube and arms to support the air-tubes, oil-supply connections, and a subburner surrounding the discharge end of the vaporizing-tube and communicating with the casing.

In testimony whereof I have signed this specification in the presence of two subscribing witnesses.

GEORGE WASHINGTON.
